(57) **CLAIM**

The ornamental design for a mobile phone leather sheath, as shown and described.

DESCRIPTION

FIG. 1 is a rear, top and left perspective view of a mobile phone leather sheath showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a front, top and left perspective view of the mobile phone leather sheath of FIG. 1 shown with an unclaimed mobile phone.

FIG. 9 is another perspective view of the mobile phone leather sheath of FIG. 8 in a state of use with an unclaimed mobile phone.

FIG. 10 is another perspective view of the mobile phone leather sheath of FIG. 8 in an alternate state of use with an unclaimed mobile phone; and,

FIG. 11 is another perspective view of the mobile phone leather sheath of FIG. 8 in an alternate state of use with an unclaimed mobile phone.

The broken lines in FIGS. 8-11 depict an unclaimed mobile phone.

1 Claim, 11 Drawing Sheets
